UNITED STATES PATENT OFFICE.

LEON DE COSTA AND WILLIAM BIRNS, OF NEW YORK, N. Y.

HAIR-CUTTING DEVICE.

Application filed September 28, 1927. Serial No. 222,468.

This invention relates to hair cutting devices and more particularly to means for transforming a safety razor into a hair cutting implement.

5 The principal object of the invention is to provide an attachment to a safety razor which will keep the blade in a certain position so it can be used for cutting hair.

10 Another object of the invention is to provide a device of this character which can be readily attached to a safety razor and which can be easily detached so the razor can be used for shaving purposes.

15 Other objects will appear as the disclosure progresses. The drawings are intended merely to indicate a possible embodiment of the invention. It is obvious therefore that the actual needs of manufacture may necessitate certain mechanical changes. It is 20 therefore not intended to limit the invention to the embodiment illustrated, but rather to define such limits in the appended claims.

25 For a more detailed understanding of the invention attention is now called to the drawings in which a preferred embodiment is shown illustrated.

Figure 1 is a side view of the attachment showing it applied to a safety razor.

Fig. 2 is a front view thereof.

30 Fig. 3 is a perspective view of the attachment.

Fig. 4 is a front view thereof.

Fig. 5 is a section on line 5—5 of Fig. 4.

35 The safety razor illustrated is that known as an "Autostrop" to which the attachment is mainly adapted to.

40 Referring to the drawings in detail in which like reference characters denote like parts throughout the specification, numeral 1 denotes the safety razor, 2 the razor blade, and 3 the attachment for positioning the blade so it can be used for cutting hair.

45 In razors of this style the shaving position of the blade is that shown in the dot and dash line 4 or when the cutting edge of the blade rests in the end grooves 5.

50 For forming the razor into a hair cutting device the attachment 2 is placed on the razor frame as shown in Fig. 1 with the lower edge 6 in the groove 5 where the edge of the blade rests when used for shaving, and the cutting edge 7 of the blade placed in the grooves 8 of the attachment.

The upper part of the attachment is formed with a curved portion 9 so it will snugly fit on the holder. Leading outward from the portion 9 are a pair of arms 10 and behind the said arms is a cross member 11 for strengthening the device and at the same time forming a lip which rests in the groove 5 of the razor holder. As noted in Fig. 2 the space between the arms 10 is wide enough for the razor blade to cut the hair in an efficient manner.

55 It will thus be seen that we have provided an efficient and simple attachment for turning a safety razor into a hair cutting device. The attachment can easily be slipped on and off the razor holder and thus make the instrument do double service, that of shaving 60 and hair cutting.

65 Having described our invention, we claim:

1. The combination with a safety razor including a razor blade and a razor frame having a groove, of a blade holding member adapted to be supported at the lower end in said groove and the upper end on said razor frame, said blade holding member having a curved portion at the top for fitting onto said razor frame, a pair of arms extending outwardly, the bottom of said arms leading to a cross member, a lip formed in said cross member for fitting into said groove of the razor frame and means in said blade holding member for the positioning of the said blade 70 so it can be used for cutting hair.

75 80 85 90 95 100
2. The combination with a safety razor including a razor blade and razor frame having a groove, of a blade holding member adapted to be supported at the lower end in said groove and the upper end on said razor frame, said blade holding member having a curved portion at the top for fitting onto said razor frame, a pair of arms extending outwardly from the curved portion and leading to a cross member, a lip formed in said cross member for fitting into said groove of the razor frame, a groove formed in said blade holding member for positioning the said blade at a proper angle so it can be used for cutting hair.

105 3. The combination with a safety razor including a razor blade and razor frame having a groove, a blade holding member adapted to be supported at the lower end in said groove and the upper end on said razor frame,

said blade holding member having a curved portion at the top for fitting onto said razor frame, a pair of arms extending outwardly from the said curved portion and leading to a cross member, said cross member being at an acute angle with respect to the said arms and forming a groove for positioning the

said blade at a proper angle for cutting hair, and a lip formed in said cross member for fitting into said groove of the razor frame. 10

In testimony whereof we affix our signatures:

LEON DE COSTA.
WILLIAM BIRNS.
